UNITED STATES PATENT OFFICE.

FRANZ JERNETZ AND FERDINAND JENICZEK, OF VIENNA, AUSTRIA-HUNGARY.

CONTRIVANCE FOR DIMINISHING THE DANGER TO FOOT-PASSENGERS FROM STREET-RAILWAYS.

SPECIFICATION forming part of Letters Patent No. 519,911, dated May 15, 1894.

Application filed October 14, 1893. Serial No. 488,190. (No model.)

To all whom it may concern:

Be it known that we, FRANZ JERNETZ and FERDINAND JENICZEK, of Vienna, Austria-Hungary, have invented a new and useful

5 Contrivance for Diminishing the Danger to Foot-Passengers from Street-Railways, of which the following is a specification, reference being had therein to the accompanying drawings.

10 This invention relates to automatic guards or protectors for tram cars and similar vehicles to remove any person or object lying on or between the rails or to prevent their being run over.

15 A guard or protector constructed according to this invention is normally raised from the ground but is automatically lowered into its operative position on the approach of the car to any obstacle. After the obstacle has been 20 removed the guard or protector can be easily raised by the driver.

The accompanying drawings illustrate in what manner this invention may be carried into effect.

25 Figure 1 is a side elevation of the lower part of a car furnished with the improved guard or protector. Fig. 2 illustrates it in end elevation. Fig. 3 is a plan of the guard or protector adapted for use with large cars. Fig.

30 4 illustrates a similar view of a guard or protector for use with smaller cars. Figs. 5, 6, 7 and 8 are illustrations of details of the apparatus drawn to an enlarged scale, and Fig. 9 is a detail front elevation of a modification.

35 The apparatus consists essentially of two parts, the guard or protector A and the actuating device B. The guard A is ordinarily held up in the position indicated by the dotted lines in Fig. 1 and is automatically lowered 40 into the position shown by the full lines when

the actuating or indicating device B comes into contact with any obstacle. To allow of the desired movement the guard A is hinged or pivoted to the hanging plates p by means of bolts r. (Fig. 2.) The front end of the guard A is suspended by means of a link s from one end of a lever a the other end of which is connected at o to vertically moving rods or bars b which pass up and through the 45 floor of the car so that they can be depressed by the driver or conductor to raise the guard

or protector. The lever a is pivoted in the lug g. The raised position of the guard is indicated by the dotted lines in Fig. 1.

The apparatus for maintaining the guard 55 in its highest position is illustrated in Figs. 1, 2, 5, 6 and 8. Two suitable arms d are hinged to the bracket h secured to the car floor and are arranged to pass one on each side of the lever a. Springs e are combined 60 with the arms d and press against pins i so that the lower ends of the arms are continuously pressed forward. Each of the arms d is formed with a step or projection which engages with a transverse pin or plate c secured 65 to the lever a and normally prevents its ascent and the consequent descent of the guard. A board or plate f preferably formed of wood, or a roller f' (Fig. 8) is secured to the lower ends of the arms d and has resting against it 70 part of the actuating device B. This actuating device B consists of a hinged plate or series of connected vertical rods pivoted in the brackets k. The rods composing the series are suitably stayed and connected together 75 and are held in position by means of the spring m and the chain n. The height of the lower edge of the actuating device from the rails and ground can be adjusted by means of the nuts l.

80 The operation of the apparatus is as follows:—If, during the running of the car, the lower edge of the actuating device B comes into contact with an object or person lying on the ground, then the device B is moved backward 85 carrying the arms d with it as shown in the full lines Fig. 1. The steps on the arms d are thus moved out of engagement with the projections c and the guard A is free to descend to the operative position. The extent of the descent of 90 the guard A may be limited by a stop combined with the lever, or, and preferably, by a small wheel or wheels u which come into contact with the ground or rails. After the obstacle has been removed the driver restores the 95 guard to its original position by depressing the rods b with his foot, thus lowering the front end of the lever a and raising the guard A. Under the influence of the springs e the arms d are moved forward and again engage 100 with the projections on the lever a.

The apparatus hereinbefore described is

duplicated, one set being placed on each end of the car so as to be available for use in whatever direction the car is running. The apparatus at the rear of the car may be locked 5 in its inoperative position by means of the cranked rod *w* furnished with a folding handle *y* and mounted so as to rotate in the eyes or rings *z*.

For greater safety and to prevent the possibility of any person becoming entangled with the actuating device *B* it may be constructed as shown in Fig. 9 and covered with wire gauze or similar material.

The positions of the various parts of the apparatus when the guard is in its lowest position are indicated in Fig. 1 by full lines.

What I claim, and desire to secure by Letters Patent of the United States, is—

1. An automatic guard for railway, tram 20 cars and similar vehicles, consisting of the hinged vertically moving shield *A* suspended by the lever *a* which carries the pins or plates *c*, the catch bars *d* capable of engaging with the pins or plates *c* and furnished with the rail *f*, springs *e* engaging with the catch bars 25

d, vertically moving rods *b* attached to the lever *a* and furnished with a foot plate, and a hinged plate or frame *B* substantially as set forth.

2. In an automatic guard for cars, the lever 30 arranged to support the movable shield, spring-controlled catches arranged to press upon the lever and hold the shield in inoperative position, and means for disengaging the catches upon approaching an obstacle; 35 substantially as described.

3. In an automatic guard for railway and tram cars and similar vehicles, a lever *a* from one end of which the shield *A* is suspended the other end being furnished with the projections *c* and the rods *b* carrying a foot plate, 40 substantially as set forth.

In witness whereof we have hereunto set our hands in presence of two witnesses.

FRANZ JERNETZ.

FERDINAND JENICZEK.
